(57) **CLAIM**

The ornamental design for a helmet nape pad, as shown and described.

DESCRIPTION

FIG. 1 is a rear perspective view of a helmet nape pad showing our new design;

FIG. 2 is a front perspective view of the helmet nape pad shown in FIG. 1;

FIG. 3 is a rear elevational view of the helmet nape pad shown in FIG. 1;

FIG. 4 is a front elevational view of the helmet nape pad shown in FIG. 1;

FIG. 5 is a left-side elevational view of the helmet nape pad shown in FIG. 1;

FIG. 6 is a right-side elevational view of the helmet nape pad shown in FIG. 1;

FIG. 7 is a top plan view of the helmet nape pad shown in FIG. 1; and,

FIG. 8 is a bottom plan view of the helmet nape pad shown in FIG. 1.

The broken lines shown in the drawings represent portions of the helmet nape pad that form no part of the claimed design.
